UNITED STATES PATENT OFFICE.

MASON B. GIBERSON, OF MUNCIE, INDIANA, ASSIGNOR OF ONE-HALF TO
BURT H. WHITELEY, OF SAME PLACE.

CAR-COUPING.

SPECIFICATION forming part of Letters Patent No. 638,505, dated December 5, 1899.

Application filed June 21, 1899. Serial No. 721,290. (No model.)

To all whom it may concern:

Be it known that I, MASON B. GIBERSON, a citizen of the United States, residing at Muncie, in the county of Delaware and State of Indiana, have invented certain new and useful Improvements in Car-Couplers, of which the following is a specification, reference being had therein to the accompanying drawings.

This invention relates to certain new and useful improvements in car-couplers.

The general object of this invention is, first and broadly, to provide a locking-bar with means for preventing it from jarring out of locking position in its relation to the knuckle, and, second and specifically, to provide a locking-detent for such locking-block, such locking-block having a lifting-pin loosely connected therewith, so that an initial movement of such pin will disengage such detent from such block, whereby the further movement of such pin will act to lift the locking-block out of locking position.

The second object of my invention is to provide for returning the locking-block to locking position in those cases in which the purpose to cut or couple two cars is suddenly changed to a purpose not to cut or uncouple them; and this feature of my invention has to do with returning the locking-block to locking position before the knuckle has been swung out of locking position, although the locking-block has been momentarily elevated to unlocking position, and this object is effected by so arranging the lifting-pin, locking-block, and the guide-pin for the latter that by the lateral thrust of the elevated lifting-pin it will shift the foot of the locking-block from its supporting-shoulder in the head and allow it to drop down into locking position.

This invention also relates to details of construction and arrangement hereinafter appearing, and particularly pointed out in the claims.

In the accompanying drawings, on which like reference-letters indicate corresponding parts, Figure 1 is a sectional view of my improved coupler on the line $x-x$ of Fig. 2; Fig. 2, a side elevation of the same; Fig. 3, a cross-sectional view on the line $y-y$ of Fig. 1 and showing the locking-block held in locking position by a locking-dog; Fig. 4, a similar view

to Fig. 3, showing the locking-dog out of locking engagement with the locking-block and in a position to permit such block to be elevated; Fig. 5, a similar view to Fig. 3, but 55 showing the locking-block out of engagement with the swinging knuckle; Fig. 6, a similar view to Fig. 3, showing the manner in which the locking-block is held out of locking contact with the swinging knuckle; and Fig. 7, a 60 detail perspective view of the lifting-pin, locking-block, and locking-dog and also showing their relative relation to each other.

The letter A represents a car-coupler draw-bar having a head B. To this head is pivotally connected a swinging knuckle C by means of a pin D or in any other suitable manner. This knuckle has a shank E normally projecting within the head and adapted to be locked therein, so that the forward end F of 70 said swinging knuckle may normally stand partially across the forward end of the coupler. Such forward end of the knuckle is provided with a hole or opening G for the reception of a pin for use in connection with an 75 ordinary link-and-pin coupling, it being understood that such forward end is bifurcated, as clearly illustrated in Fig. 2, the space for the reception of such link being indicated at H, (see Fig. 2;) but to this special construction I lay no claim, as my invention has reference, among other things, to means for holding this locking-block down in locking position, as illustrated in Figs. 1 and 2.

The letter I represents a locking-block 85 sloping or beveled at its lower end, as seen at a, to permit its more ready withdrawal from between the knuckle E and guide W and also having an elongated opening or slot, as shown at J, within which projects a stud K, extending from a lifting-pin L, such lifting-pin extending above the upper wall of the head B through the hole M, the hole being considerably larger than the pin. The outer end of this pin is provided with a hole O for the attachment of operating devices. A shoulder P, formed on the pin, limits its downward movement. From this description it will be seen that as the pin is raised the stud K will move from the lower end of the slot J to its 90 upper end in the locking-block, and when still further raised the locking-block itself will be 95 100

moved out of engagement with the inner arm E of the swinging knuckle, as illustrated in Fig. 5.

I will now refer to the preferred form of means for holding the locking-block normally in its locking position, so as to prevent it from being raised when it is unduly jarred, as when traveling over rough roads. From Figs. 2 to 7, inclusive, it will be seen that upon a pin Q, extending within a hole or opening R in the head B, (see dotted lines in Fig. 2 particularly,) is mounted a locking-pawl F, which extends over the stud K and down upon the locking-block I and abuts against a stop I'. This locking-pawl prevents the locking-block from being elevated or withdrawn from its locking position until after the locking-pawl has moved out of locking engagement therewith, which is accomplished by raising the pawl K through the lifting-pin L until the stud reaches the upper end of the slot J, by which time the locking-pawl is moved out of locking contact with the locking-block to permit such locking-block to be elevated. Thus it will be seen that my invention, broadly, has reference to means to hold the locking-block in locking position, and specifically it has reference to a locking-pawl, which pawl may be moved out of engagement with said block before the block is elevated by the lifting-pin, such lifting-pin carrying a stud projecting within an elongated opening or slot in the locking-block to permit this to be accomplished.

I will now refer to the manner in which the locking-block is normally held out of engagement with the swinging knuckle. Referring again to the pin Q, it will be observed that it passes through the slot T in the locking-block. While this slot permits the locking-block to be elevated, as above described, it also permits the block to pivot about said pin, and thereby perform a very useful function, as will shortly appear. Let us suppose that the lifting-pin has been elevated sufficiently to release the locking-block from engagement with the swinging knuckle. In this position the block will swing into engagement with the shoulder U of the interior of the housing B, where it will be held out of locking position until the brakeman cant the lifting-pin to the position illustrated in dotted lines in Fig. 6, which will cause the locking-block to pivot about the stationary pin G and out of engagement with the shoulder U, so that it can again quickly drop into locking position. The locking-block swings into engagement with the shoulder U by reason of the preponderance of weight of the locking-block B being at one side of its pivotal connection of the lifting-pin—that is, on the side away from the shoulder U. From Fig. 1 particularly it will be seen that a guideway W is formed in the inner wall of the housing in front of the shoulder U. This is for the purpose of guiding the locking-block and holding it more firmly in position. Thus with my invention, while I have provided for locking the locking-

block so that it cannot be accidentally raised from engagement with the swinging knuckle, due to shocks and jars, &c., and also for holding the locking-block out of locking engagement with said swinging knuckle, it will be understood that such locking-block may be instantly thrown to locking position while the swinging knuckle is in coupling position, such position being illustrated in the drawings. This is of particular advantage, especially when a signal has been given to "cut the cars" for switching, &c., and the signal is suddenly given not to cut them. Consequently without the necessity of separating the cars and then bringing them together again the locking-bar may be quickly thrown to locking position by the brakeman simply canting the lifting-pin, and thereby pivoting said locking-block about the fixed pin out of engagement with the shoulder U, thereby again coupling the cars, which saves a great amount of time and annoyance.

Having thus fully described my invention, what I claim as new, and desire to secure by Letters Patent, is—

1. In a car-coupler, the combination with a draw-bar, having a head at one end, of a knuckle swingingly mounted thereon, a locking-block adapted to engage with said knuckle to lock it in position, said block having an elongated or slotted opening therein, a lifting-pin adapted to engage with said locking-block and move independently thereof the length of said slot and then to lift said block, and a locking device adapted to be operated out of locking contact with said locking-block during said initial movement of said lifting-pin, substantially as described.

2. In a car-coupler, the combination with a draw-bar having a head formed thereon at one end, of a locking-knuckle swingingly mounted thereon, a locking-block adapted to hold said knuckle in locking position, said locking-block having an elongated opening or slot therein, a lifting-pin, a stud or projection extending from said pin and adapted to project within said slot, a locking-dog pivotally mounted in said head and extending over said stud and adapted to lock said locking-block in locking position, and also adapted to be thrown out of locking position by the movement of said stud within said elongated opening, said lifting-pin projecting through a hole or opening in said head, substantially as shown and described.

3. In a car-coupler, the combination with a draw-bar having a head at one end, of a locking-knuckle swingingly mounted thereon, a locking-block adapted to engage with said knuckle to hold it in locking position, said block having an elongated opening or slot therein, a lifting-pin projecting through a hole or opening in said head, a stud carried by the inner end of said lifting-pin and adapted to project within said elongated opening, a pin projecting through the slot in said locking-block and fixed in said head, a locking-

dog pivoted upon said pin and extending over said stud into engagement with said locking-block to lock said block in locking position, and a shoulder formed in said head with 5 which said locking-block engages when in its unlocked position.

4. In a car-coupler, the combination with a draw-bar having a head at one end, of a locking-knuckle swingingly mounted thereon, a locking-block adapted to engage with said knuckle to hold it in locking position, a stop projecting from said locking-block, a locking-pawl pivotally mounted in said head and adapted to engage with said locking-block 10 and abut against said stop, a lifting-pin extending upward through said head, a stud or projection extending from one side of said lifting-pin into an elongated opening in said head and beneath said locking-pawl, all substantially as shown and described.
- 15 5. In a car-coupler, the combination with a draw-bar having a head formed at one end thereof, of a locking-knuckle swingingly mounted thereon, a locking-bar within said head adapted to hold said knuckle in locking position, a stop extending from said block, said block having an elongated opening and a slot therein, a fixed projection through said slot to guide said locking-bar as it is moved 20 into and out of locking position, and also acting as a pivot for said locking-block, a lift-

ing-pin carrying a stud adapted to project within said elongated opening in the locking-block, a pivoted locking-pawl mounted on said fixed pin and extending over said stud and engaging with said locking-block and abutting against said projection, said lifting-pin being adapted to throw the locking-dog out of locking engagement with the locking-block and swing said block, and a shoulder 25 formed within the walls of said head with which said locking-block engages when it is swung by the lifting-pin, substantially as shown and described.

40 6. In a car-coupler, the combination with a draw-bar having a head formed at one end thereof, of a locking-block having a slot therein, a fixed pin carried by said head and projecting through said slot, a shoulder in said head upon which said block rests when in unlocking position, and a lifting-pin pivotally connected with said locking-block and adapted to be canted to pivot said block about said fixed pin and out of engagement with said shoulder.

45 In testimony whereof I affix my signature in presence of two witnesses.
